JOURNAL BRASS TRIMMER

William T. Bissell, Indianapolis, Ind., assignor to
 Journal Box Servicing Corporation, Indianapolis, Ind., a corporation of Indiana

Application June 9, 1938, Serial No. 212,754

6 Claims. (Cl. 90—24)

This invention relates to a machine, portable in nature, especially designed to trim railroad equipment journal brasses in carrying out the invention as shown and described in the co-pending application on Restoration of car journal brasses, filed in the United States Patent Office June 1, 1936, and bearing the Serial Number 82,858.

The present invention has for a primary purpose the provision of a specialized machine that may be operated by the repair men directly at the side of the car, the journal brasses of which are being removed for inspection and correction in accordance with said invention. It is the customary procedure to install an original journal brass having a Babbitt metal lining with a greater degree of curvature than that of the journal. After such a brass has been in operation under load for a period of time, it frequently happens that as the soft lining becomes rolled and pressed to conform to the curvature of the journal, some of this metal lining will be worked out on either or both edges of the brass to protrude in such manner that proper lubrication of the journal is prevented. Ordinarily such a brass, upon inspection, is removed from the journal and discarded as being unusable and a new brass is put in its place to be subjected to the same action.

By means of the present invention, this brass which is found to have the Babbitt metal overrunning the edges of the brass is placed in the machine of the type herein described and these edges are trimmed off to the required degree and then that same brass is returned to its own journal on which it was worn so that the advantages of the uniform bearing contact secured under the load conditions are retained, in addition to the effecting of a great saving in money by not having to discard that particular brass.

Not only does this machine trim the brass as indicated but it is arranged in such a form that the trimming may be done right at the side of the car while it is jacked up so that there is no danger of the brass from one particular journal becoming interchanged with the brass of another journal. Furthermore, the machine as conforming to the present invention is easily operated and adjusted so that it may be confined entirely to hand operation without having to bother with electrical, steam or air connections for power.

These and many other objects and advantages will become apparent to those working in this same art in the following description of one

particular form of the invention as illustrated in the accompanying drawings, in which

Fig. 1 is a rear perspective view of a machine embodying the invention in a position ready for use;

Fig. 2, a side elevation on a reduced scale showing the machine in a position for transportation;

Fig. 3, a front view in perspective of the machine;

Fig. 4, a detail in front perspective view of the shaper bed;

Fig. 5, a vertical transverse section on the line 5—5 in Fig. 4;

Fig. 6, a vertical longitudinal section on the line 6—6 in Fig. 4;

Fig. 7, a detail in rear perspective view of the shape of the bed; and

Fig. 8, a detail in vertical longitudinal section on the line 8—8 in Fig. 7.

Like characters of reference indicate like parts throughout the several views in the drawings.

A frame is formed comprising essentially the side rails 10 and 11; the rear supporting legs 12 and 13 with braces 14, 15 extending from their lower ends forwardly and upwardly to the respective side rails; and a pair of front wheels 16 and 17 carrying an axle 18 to which the forward ends of the side rails 10 and 11 are secured. Suitable handles 19 and 20 are secured to the rails 10 and 11 and extend rearwardly to permit the lifting of the rear end of the frame thereby and pushing it about on the wheels 16 and 17 in the manner of pushing a wheelbarrow, except that two wheels are provided in this instance for stability.

A pair of longitudinally spaced apart cross shafts 21 and 22' are rockably carried by the side rails 10 and 11 and these shafts respectively carry the upwardly extending legs 22, 23 and 24, 25. The upper ends of these legs rockably engage bed rails 26 and 27.

The shafts 21 and 22' are mounted toward the rear portion of the frame so that the bed rails 26 and 27 may be lowered and raised in parallel relation with the side rails 10 and 11, as indicated in Fig. 2 where the solid lines indicate the parts in their lowered positions and the dash lines, in the elevated positions.

This lowering and raising of these parts is accomplished and controlled by means of a gear segment 28 rockably mounted on the shaft 21 and fixed to a cross bar 29 inter-engaging the forward legs 22, 23. The peripheral teeth of the gear 28 engage with a worm 30 which is mount-

ed on a crank shaft 31 supported between a cross bar 32 and a bracket 33. Thus by turning the crank 31 by means of the handle 34, the gear 28 is revolved to carry the cross bar 29 therewith and thus lift the gears 22, 23 thereby. Through this shifting the bed plates 26 and 27 are obviously raised and lowered. The purpose of changing the elevation of these rails 26, 27 is to lower the mechanism to be carried thereon, as will hereinafter be described, so as to permit ease of transportation and to lower the center of gravity of such parts during the transportation, and at the same time permit raising of the parts to a proper working height for convenience of the operator.

Secured to the rails 26, 27 is a bed 35. This bed is generally U-shape in cross section and carries by the upturned ends a pair of guides 36, 37 having under and inwardly sloping faces serving to receive thereover and around a carriage 38. This carriage 38 is shiftable along the bed by means of a spur gear 39, Fig. 4, meshing with a rack gear 40 secured to the underside of the carriage, the spur gear being mounted on a transverse shaft 41 turned by means of a hand wheel 42 at the side of the bed.

This carriage 38 has a brass holder 43 carried on its upper side in a manner to permit up and down and lateral movement after the brass 44, Fig. 1, is clamped thereon. This holder is provided with a rear abutment 45 against which the rear end of the brass 44 may rest in an upside-down position, the holder being provided with a transverse groove 46 at this abutment 45 to accommodate the projecting flange of the brass. The rear end of the holder is hinged on a transversely extending pin 47 which is carried across a head 48, Fig. 8. This head 48 is horizontally shiftable about a vertical axis and has a cylindrical foot 49 slidably entered in a like counterbore in the carriage 38 and is there retained against displacement by means of a screw 50 entering from the bottom of the carriage and screw-threadedly engaging the foot 49. Thus the holder 43 may be lifted and lowered by its forward end to hinge on the pin 47 and may also be shifted by its forward end laterally over the carriage 38 by turning of the foot 49 on the carriage.

The brass 44 is secured in position on the holder 43 by means of a jaw 51 slidably engaging the forward end of the holder 43 in the nature of a carriage and arranged to be shifted back against the forward end of the brass so as to force the brass back into compressive engagement with the abutment 45. Movement of the jaw 51 is had by means of a screw 52 engaging therewith and connecting through a shaft 53, Fig. 5, with an operating crank 54, Fig. 4. The shaft 53 is carried through a head 55. This head 55 is fixed to the holder 43 to be shiftable therewith.

This head 55 is received between a pair of upturned legs 56 and 57 of a slide 58 which is guided in cross travel on the carriage 38 by means of a tongue 59 entering a slot 60 in the carriage. Transverse shifting of the slide 58 is accomplished by turning a hand wheel 61 which is mounted on a shaft 62 screw-threadedly passing through a leg 64 upturned at one side of the forward portion of the carriage 38 and inter-engaging with the carriage slide 58, as indicated in Fig. 5. The end of the screw shaft 62 has a reduced neck portion and a head 63 therebeyond so as to receive a downturned lip of the slide 58

about that neck portion whereby the slide 58 will travel crosswise of the carriage 38 in that direction as the hand wheel 61 may be turned. This operation creates the horizontal shifting of the holder 43.

For vertical travel of the holder 43, the slide 58 carries a wedge 65 between the upturned legs 56 and 57 and this wedge is shifted laterally therebetween by means of a hand wheel 66 turning a screw shaft 67 passing through the leg 56 and screw-threadedly engaging the wedge 65. The under-face of the head 55 of that portion which fits between the legs 56 and 57 is inclined and bears against the top face of the wedge 65, whereby shifting of the wedge 65 laterally there-across will lift the head 55 in one direction and permit it to drop in the other.

The desired degree of elevation of the work holder 43 resulting from manipulation of the hand wheel 66 is maintained by a securing screw 68 vertically passing down through the head 55 out of the path of the wedge 65 and screw-threadedly engaging the carriage 38 thereunder, Fig. 6. The head 55 is slotted so as to permit lateral shifting of the head 55 in relation to the screw for the lateral adjustment above indicated.

In the description so far given, mechanism has been described for the receiving and holding of the brass 44 in position to be reciprocated by the carriage 38 in a fore and aft travel along the bed 35 as produced by turning of the hand wheel 42.

Since it is the usual case that both edges of the brass must be trimmed, it is preferable that a pair of tool holders be provided in order that individual adjustment thereof as well as of the brass itself may be reduced in order to save time. In the form herein shown, in order to provide a mounting for the tool holders, a pair of standards 69 and 70 are secured to the respective sides of the bed 35 to extend upwardly therefrom and carry a guide bar 71 across the bed and spaced a distance thereabove. This bar 71 is provided with any type of suitable guides, herein shown as having the top and bottom edges beveled to receive a tool carriage 72 thereon. This carriage 72 is caused to travel along the bar 71 by means of a shaft 73 carried by the upper ends of the standards 69 and 70 and turned by means of hand wheels 74 and 75, one on each end of the shaft 73. This shaft 73 has a central worm gear 76 thereon which screw-threadedly engages through a projection 77 mounted on the carriage 72.

This carriage 72 has mounted thereon on its forward side the spaced apart tool holders 78 and 79 each hanging from its respective screw shafts 80 and 81 which extend upwardly through forwardly turned shoulders 82 and 83 to be operated by their own individual cranks 84 and 85. Each tool holder 78 and 79 carries a hingedly mounted block 86 onto which the tool 87 is clamped from the forward side, the block 86 being free to swing forwardly but restricted from swinging rearwardly by coming into contact in that direction by their respective holders. These holders 78 and 79 are maintained in vertical alignment by engaging guides formed on the forward side of the carriage 72.

The individual tool 87 may be lowered into contact with the brass 44 and adjusted laterally for the proper size cut by means of either hand wheel 74 or 75 and also vertically for the depth of cut by means of the crank 84 or 85 as the case may be. Preferably, particularly since in the

present form, the tool holders 78 and 79 are not individually adjustable one in relation to the other laterally, one tool 81 is maintained at an elevation so that it will not cut on the side of the brass opposite from that side to which the tool 81 is being adjusted. The cut is made by turning the hand wheel 42 to carry the brass 44 rearwardly past the tool, and then upon return forward travel, the tool 81 will be lifted out of the way without cutting. When the one edge 10 is trimmed, then the other tool 81 may be likewise adjusted for the cut on the other side of the brass.

The trimmings cut from the brass may drop down on either side of the bed 35 between the rails 36 and 37 into a suitable collector pan 88 which is secured to the rails under the bed. Since the machine is to be used out of doors, a suitable housing 89 is provided consisting of side and end walls and over which a cover 90 may be placed, the cover being preferably hinged, as at 91, Fig. 3, to the forward and end wall of the housing 89 so that the cover may be lifted up out of the way when the machine is in use and then dropped back down over the shaper for protection from the weather. Then when the machine is to be moved to the next scene of operation, such as the other end of the car or to the next car, or is to be carried back to the central shop, the entire shaper mechanism may be lowered down toward the rails 10 and 11, as above indicated.

Since the shaper necessarily has considerable weight, the cart for transporting it is preferably counterbalanced in some respect. I secure this counterbalancing effect by mounting a cabinet 92 forwardly of the axle 18 on a continuing part of the side rails 10 and 11 which are dropped down and extend forwardly under the cabinet as a means for its support. This cabinet 92 is provided with suitable compartments for carrying tools and extra brasses for the convenience of the operator. Such tools, and particularly brasses, have considerable weight and since these articles are carried in the cabinet forwardly of the axle 18, there will be a counterbalancing effect achieved thereby at the same time affording convenience to the operator.

While I have herein shown and described my invention in the one particular form, it is obvious that structural changes may be employed without departing from the spirit of the invention, and I, therefore, do not desire to be limited to that precise form beyond the limitations as may be imposed by the following claims.

I claim:

1. In a portable journal brass trimmer, a vehicle carrying a cutting device, and means for raising and lowering the device for use in one position and transportation in the other, a frame, handle extensions at one end of the frame, an axle at the other end of the frame from the handles supporting the frame, said device being mounted on the frame to one side of the axle to be lowered toward the axle, and counterbalancing carrying means carried by the vehicle on the other side of the axle.

2. In a portable journal brass trimmer, a vehicle carrying a cutting device, and means for raising and lowering the device for use in one position and transportation in the other, a frame, handle extensions at one end of the frame, an

axle at the other end of the frame from the handles, said raising and lowering means comprising members rockably attached to the frame and constrained to rocking in parallel vertical planes toward the handles to raise and toward the axle to lower, and means interconnecting the device with the rockable members.

3. In a portable journal brass trimmer, a vehicle carrying a cutting device, and means for raising and lowering the device for use in one position and transportation in the other, a frame, handle extensions at one end of the frame, an axle at the other end of the frame from the handles, said raising and lowering means comprising members rockably attached to the frame and constrained to rocking in parallel vertical planes toward the handles to raise and toward the axle to lower, and means interconnecting the device with the rockable members, a gear sector pivoted on the vehicle at the handle end and interengaged with said rockable members, and a gear meshing with the sector for rotation thereof.

4. In a manually moved carriage for transporting cutting means, a pair of wheels, a frame supported at one end by the wheels, handles at the other ends of the frame from the wheels for lifting that end and pushing the carriage, front and rear rocker members hingedly supported by the frame, a cutting device support base hingedly connecting with upper portions of said rocker members whereby the base may be raised toward the handles and lowered in relation to said frame toward and close to the wheels, and means located and close to the wheels for maintaining said base at selective positions of elevation.

5. In a manually moved carriage for transporting cutting means, a pair of wheels, a frame supported at one end by the wheels, handles at the other ends of the frame from the wheels for lifting that end and pushing the carriage, front and rear rocker members hingedly supported by the frame, a cutting device support base hingedly connecting with upper portions of said rocker members whereby the base may be raised toward the handles and lowered in relation to said frame toward and close to the wheels, and means located at the handle end of the frame for maintaining said base at selective positions of elevation, said maintaining means comprising a gear carried by one of said rocker members, a second gear carried by said frame to mesh with the rocker gear, and means for turning the frame gear.

6. In a manually moved carriage for transporting cutting means, a pair of wheels, a frame supported at one end by the wheels, handles at the other ends of the frame from the wheels for lifting that end and pushing the carriage, front and rear rocker members hingedly supported by the frame, a cutting device support base hingedly connecting with upper portions of said rocker members whereby the base may be raised toward the handles and lowered in relation to said frame toward and close to the wheels, and means for maintaining said base at selective positions of elevation, said rocker members being located rearwardly of said wheels, and cabinet balancing weight carrying means being carried by said frame forwardly of said wheels.

WILLIAM T. BISSELL.
